US0D1085056S

(12) **United States Design Patent** (10) **Patent No.:** **US D1,085,056 S**
(45) **Date of Patent:** **** Jul. 22, 2025**

(54) **EARPLUG**

(71) Applicant: **TONGHENGJI (SHENZHEN)
TECHNOLOGY CO., LTD**, Shenzhen
(CN)

(72) Inventor: **Zhi Ouyang**, Shenzhen (CN)

(73) Assignee: **TONGHENGJI (SHENZHEN)
TECHNOLOGY**, Shenzhen (CN)

(**) Term: **15 Years**

(21) Appl. No.: **29/814,041**

(22) Filed: **Nov. 3, 2021**

(51) LOC (15) Cl. **24-01**

(52) U.S. Cl.

USPC **D24/106**; D14/223

(57) **CLAIM**

The ornamental design for an earplug as shown and described.

DESCRIPTION

FIG. 1 is a perspective view of an earplug showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
